UNITED STATES PATENT OFFICE.

JEREMIAH FRANK SMITH AND MARGARET A. SMITH, OF KEOKUK, IOWA.

TOY PROJECTILE.

SPECIFICATION forming part of Letters Patent No. 442,464, dated December 9, 1890.

Application filed September 17, 1889. Serial No. 324,238. (No model.)

To all whom it may concern:

Be it known that we, JEREMIAH FRANK SMITH and MARGARET A. SMITH, citizens of the United States, residing at Keokuk, in the county of Lee and State of Iowa, have invented certain new and useful Improvements in Toy Projectiles; and we do hereby declare the following to be a full, clear, and exact description of the invention, such as will enable others skilled in the art to which it appertains to make and use the same.

This invention relates to projectile toys; and its object is to provide means whereby a dart or an arrow may carry in its upward flight a folded parachute, means whereby the parachute may be released so that it may spread out by the turning of the projectile to descend, and means whereby either the projectile or some other object may serve as a load to keep the parachute right side up, thus causing the parachute to float gracefully away in the air as it slowly descends, either independently of the projectile or with the projectile as a dependent load, and affording amusement with a spice of anxiety as to where the parachute will land.

To this end our invention consists in the construction and combination of parts forming a toy projectile, hereinafter described and claimed, reference being had to the accompanying drawings, in which—

Figure I is a view of our toy in the act of floating away or slowly descending, with the projectile serving as a load. Fig. II represents the same in position to be thrown. Fig. III is a horizontal sectional view of a portion of the dart or arrow. Fig. IV represents a portion of a projectile and three parachutes, showing how a single projectile may carry up a number of parachutes; and Fig. V represents the projectile returning and the parachutes floating away in the air with different loads.

5 represents the projectile portion of the toy, and it may be either a dart provided with a side notch 6 and a feather-shaped tail 7, or it may be an arrow with any common tail end—such, for example, as that shown in dotted lines, Fig. II. A number of threads 8 may be attached at one end to the tail of the projectile, or to some other object serving as a

load, as shown at 16, Fig. V, and at the other end to the edges of a parachute 9.

10 represents a light wire hook loosely attached to the middle or top portion of the 55 parachute.

The projectile has a longitudinal bore 11 in its forward end, into which a side slot 12 opens, and in this bore a bullet 13 is placed to play freely.

14 represents an enlargement of the slot 12 to admit the bullet; or, in lieu of this enlargement, the bullet may be placed in at the front end and the end then closed by a metallic screw-head 15, as shown in Fig. III. 60

The operation is as follows: First fold the parachute like an umbrella. Then with the head of the projectile downward insert the hook 10, with its point toward the head of the projectile. Now turn the projectile-head upward and the bullet will drop in front of the hook and retain it in place. Then shoot the toy up into the air, and the parachute will be drawn head foremost through the air with little resistance until the arrow reaches its upward limit and turns its head downward to descend. Then the bullet will drop away from the hook, leaving it free to be withdrawn from the slot by the resistance of the air retarding the parachute more than it does the 75 more dense projectile, which, now pulling upon the threads 8, quickly rights the parachute, and the resistance of the air first spreads it and then impedes the descent of both 80 parachute and projectile, so that the toy is a considerable time floating in the air before it reaches the ground. 85

While the projectile may be either a dart or an arrow, we prefer the dart, because it may be thrown by any common stick and string, 90 while an arrow requires a bow or a more expensive gun to throw it.

Any weight may be substituted for the bullet 13, which will hold the hook 10 when gravitating rearward and will release the parachute when gravitating forward by the turn of the projectile.

As shown in Fig. V, other objects than the projectile may serve as a load for the parachute by attaching such load 16 to the lower 95 ends of the cords 8, and two or more parachutes may be thrown up into the air by a

single projectile, as shown in Fig. IV, in which case the turn of the projectile releases all the parachutes at once by the weight 13 falling from in front of the hooks 10. Then the parachutes may float away, carrying each its own load, free from the projectile, which may be left free to drop freely to the ground or it might yet be supported by another parachute, as in Fig. I.

10 A cord with a large knot or lug at its end might answer the purpose of the hook 10 and be an equivalent thereof.

By an arrow-shaped projectile is meant a projectile having a feather at one end and a weight at the other, or an equivalent device 15 to cause the projectile to go upward head first and then turn to come down head first.

We do not suppose that we are the first inventors of the combination of a toy parachute 20 and an arrow or other projectile for supporting the same in every manner in its upward flight, nor of every means for so connecting the parachute to the arrow that the two will be separated and fall apart at the limit of 25 their flight, and we do not make any broad claim thereto.

Having thus fully described our invention, what we claim to be new, and desire to secure by Letters Patent, is the following:

- 30 1. The combination, in a toy projectile, of a dart or arrow shaped projectile having a longitudinal bore in its forward portion and a side slot communicating with the rear end of the bore, a weight fitted to slide freely within 35 the said bore, a parachute provided with a hook at its upward point adapted to be seated in said bore, and with threads connecting its edges with the tail end of the projectile, substantially as shown and described.
- 40 2. The combination of a dart or arrow shaped projectile having an aperture in its side, a parachute provided with connections between its edges and the tail of the project-

ile, and further provided at its middle or upper portion with a hook adapted to engage 45 the said aperture, and a weight carried by the arrow and fitted to gravitate into engagement with the said hook when the arrow points upward and to gravitate out of engagement when the arrow points downward, substantially as shown and described, whereby the 50 parachute will be released at the turn of the arrow, as set forth.

3. The combination, with a dart or arrow-shaped projectile and a parachute provided 55 with a load attached by connections to its edges, of a hook and gravitating connection between the upper portion of the parachute and projectile, substantially as shown and described.

4. The combination, with a dart or arrow shaped projectile and a parachute provided with a load attached thereto by connections between its edges and the load, and a gravitating connection between the upper portion 65 of the parachute and the projectile, substantially as shown and described, whereby the 70 parachute is retained in a folded position while ascending and is automatically cast loose from the arrow by the arrow-point turning downward to descend.

5. The combination of a parachute, an arrow-shaped projectile and a gravity connection between the upper end of the parachute and the projectile, substantially as shown and 75 described, whereby the parachute will be held to the projectile when the latter heads upward and will be released therefrom when the projectile turns its head downward.

In testimony whereof we affix our signatures 80 in presence of two witnesses.

J. FRANK SMITH.
MARGARET A. SMITH.
